UNITED STATES PATENT OFFICE.

AUGUSTIN PELLERIN, OF TROUVILLE, FRANCE.

PROCESS FOR THE MANUFACTURE OF A CELLULOSE PRODUCT HAVING THE APPEARANCE OF WOOL.

Application filed February 12, 1926, Serial No. 87,993, and in France December 30, 1925.

My invention has for its object a process for the manufacture of a cellulose product having the appearance of wool, or of wool yarn, such products may be formed into 5 goods in the same manner as natural wool or wool yarn, and may have the same uses, either in the pure or the mixed state.

According to my invention, I produce in the first place filaments in any suitable manner, for instance by coagulating, by their passage through a suitable bath, the filaments issuing from dies which are supplied with a cellulose solution viscose or the like. In the known methods these filaments are 10 subjected to a constant traction or stretching from their discharge from the bath until they have acquired a certain consistency, i. e. until their molecular stability is assured, whereby they will maintain the uniform structure and brilliant aspect which 15 is due to their "setting" in the state of tension.

But in my said process, I interrupt the stretching of the filaments nearly as soon 20 as they are discharged from the coagulating bath, and their speed is reduced, or their direction of travel is changed, so that they are subjected to a certain contraction and thus assume a crape-like or crisped form 25 resembling that of natural wool. Their setting or solidification will then be completed without tension so as to leave this molecular structure unchanged.

In a preferred method, the filaments which 30 are drawn out of the coagulating bath are turned back upon themselves by abruptly changing the direction of their motion, and preferably by an obstacle placed in their path.

According to one embodiment of the invention, the set of filaments or the thread issuing from the bath is drawn upon a drum to which it adheres by reason of its humidity and which serves to draw it out. A suitably 35 disposed knife or scraper serves to remove the yarn from the surface of the drum and allows it to fall upon a second drum or like entraining device, rotating at a slower speed, which draws forward the thread without stretching it, thus leaving it in the crape-like or crisped state which it assumed by 40 reason of the slow speed and the change in direction.

The appended drawings show by way of

example a plant wherein my said process is 45 carried into effect.

Fig. 1 is a side elevation of the machine, and,

Fig. 2 is a front elevation of a part of 50 the plant.

My said plant for the manufacture of artificial wool comprises a set (usually ten) of machines such as are shown in Fig. 1.

1 is the tank containing the coagulating liquid and 2 the set of apparatus comprising dies or plates having a great number of capillary orifices and supplied with a cellulose solution under pressure by the piping 3. The set of apparatus is pivoted so that it may be removed from the tank 1. 55 The various filaments thus produced are drawn through an exit orifice 5 and are thus brought together in the form of continuous wool. The end of the tank 1 comprising the exit orifice 5 is mounted upon a machine 60 frame comprising the two cheeks 6.

The machine which serves to transform the said artificial wool essentially comprises a drum 7 in continuous rotation which is driven by a pinion 8 keyed to its shaft. Said pinion is driven by a chain 9 and a pinion 10 keyed to the shaft 11 which carries the actuating pulley 12 and the loose pulley 13. The shaft 11 is driven by a belt which can be shifted upon one of the pulleys 12 65 or 13 by suitable belt controlling means, not shown, while at the same time remaining upon the drum 14 which is keyed to the transmission shaft 15; this latter is driven by means of a progressive speed changing 70 device, not shown.

The shaft 11 carries a drum 16, and the diameters of the drums 7 and 16 and of the pinions 8 and 10 are so chosen that the periphery speed of the drum 16 shall be less 75 than that of the drum 7. I may employ for instance a periphery speed of 120 meters per minute for the drum 7 and 40 meters for the drum 16.

A member 17 forming a guide and secured 80 to the cheeks 6 is disposed at the lower part of the drum 7 for purposes, which will be hereinafter set forth, as well as the use of the pivoted blade 18 which is urged against the drum by the spring 19. The drum rotates in the direction of the arrow. The blade 18 is mounted rearwardly of the member 17 and above the latter.

A third drum 20 is driven by the drum 7 through the medium of the chain 21 and of two pinions which are keyed respectively to the shaft of the drum 20 and to the shaft 5 of the drum 7.

The operation is as follows:

When the machine is started, the wool which is at first in the irregular state and issues from the orifice 5 is brought upon the 10 drum 20 about which it is wound until it has become sufficiently regular. At this time it is cut and is brought upon the drum 7, to which it adheres by reason of its humidity and which draws it forward.

15 At the point at which the blade 18 bears against the drum 7, the wool moves upwardly, and when it is separated from the drum by the said blade, it will abruptly change its direction and will fall by its own weight. This effect of moving and change in direction is sufficient to give the crisped form to the filaments and to thus give the whole mass the appearance of wool.

The latter drops upon the drum 16 which 25 is placed at a short distance below the scraper 18 and which by reason of its reduced speed relatively to the drum 7 will only draw forward the wool at a regular rate without producing a traction which 30 would tend to destroy its crisped or woolly appearance.

I employ a group of for instance ten such machines placed side by side and suitably spaced apart to provide for the proper access, the machines being mounted upon a platform 22 in which are disposed the funnels 23, below the drums 16, in order to collect the masses of wool. The latter are guided in tubes secured to the said funnels, 35 and proceed thence into the funnels 24, in line with the first, then dropping upon the endless belt 25.

The said masses—ten in number in the present case—make up a band which is 45 drawn forward by the belt 25 and is passed between two drying rollers 26 which press out any liquid which the wool may contain. This liquid falls into a recipient and can be used again.

50 The goods may then be treated by the usual complementary operations for artificial silk, such as washing, drying and the like.

This will afford a material which forms a 55 new industrial product and which has the exact appearance of natural wool. The said mass or band may be cut into suitable lengths so that the artificial wool will be adapted for all the operations of spinning and weaving of natural wool. Like artificial silk, the substance can be dyed with facility; it may be treated alone or mixed with natural wool or like textile substances.

Instead of producing the wool in the form of a band, it may be removed in the form of

masses as discharged from the funnels 23, and such masses may be employed for spinning purposes, after a suitable twisting if necessary.

Obviously, instead of manufacturing a 70 product for carding and spinning, each of the elements as discharged from the funnels 23 may be removed, and these after a suitable twisting will serve for the manufacture of fabrics, carpets or the like. My said 75 product has a great elasticity such as is not possessed by artificial silk.

Obviously, the said invention is not limited to the construction hereinbefore set forth by way of example, and without departing from the spirit of the invention, I may modify the form, construction and arrangement of the several parts. For instance, I may give one or several backward turns to the yarn after the one produced by 85 the drum 7, whereby the crisped or woolly character of the yarn will be augmented. In like manner, as above stated, the changes in speed and direction necessary to obtain this woolly character may be obtained by other 90 means than those described.

The drum 16 serves solely to draw the material by adherence in a regular manner and to ease the part of the material which has been given the woolly appearance so as 95 to take from it the weight of the goods descending as far as the point where they are delivered to the conveyor band 25, so that the drum 16 is not absolutely essential and may be eliminated in certain plants, for instance in the case in which the vertical distance between the drum 7 and the belt 25 is short.

Having thus described my process and apparatus, what I claim as new therein, and 105 my own invention, is:

1. Process for the manufacture of a cellulose product having the appearance of wool in starting from cellulose filaments issuing from a coagulating bath by adherence to a 110 moving surface, consisting in subjecting the filaments to a backward turning upon the said moving surface so as to give them an undulated form analogous to that of natural wool.

2. Process for the manufacture of a cellulose product having the appearance of wool in starting from cellulose filaments issuing from a coagulating bath by adherence to a 120 moving surface, consisting in subjecting the said filaments upon the said surface to at least one backward turning so as to give them an undulated form analogous to that of natural wool, and in drawing the said filaments forwardly of the backward turning at a low tension so as not to destroy their undulated character.

3. Process for the manufacture of a cellulose product having the appearance of natural wool, consisting in producing cellulose 125

filaments by drawing a solution of cellulose through a coagulating bath, this drawing being obtained by a tension exerted upon the filaments, in subjecting the filaments issuing from the coagulating bath, at a point where their molecular stability will be complete, to a suppression of the said tension and at the same moment in subjecting them to a sudden backward turning which will cause them to be longitudinally turned back upon themselves, this change in the tension having for effect to give to the filaments an undulated character and a dull appearance analogous to the character and the appearance of natural wool, the filaments being subsequently washed, purified and dried.

4. Process for the manufacture of a cellulose product having the appearance of wool consisting in producing cellulose filaments

by drawing a solution of cellulose through a coagulating bath, this drawing being obtained by adherence of the filaments to a drawing moving surface to which a high speed is imparted, in causing the filaments thus drawn to meet an obstacle so as to oblige them to abruptly turn backward in being turned back upon themselves and in moving away from the said surface whereby they take an undulated form and a dull appearance, in receiving them and in carrying them away from the point of backward turning without being subjected to a tension which would risk to destroy the said character, then in washing, purifying and drying them.

In testimony whereof I have hereunto affixed my signature.

AUGUSTIN PELLERIN.
